UNITED STATES PATENT OFFICE.

HENRY W. UNCKLES, OF NEW YORK, N. Y.

CARBURETER.

1,143,092.

Specification of Letters Patent. Patented June 15, 1915.

Application filed June 16, 1914. Serial No. 845,348.

To all whom it may concern:

Be it known that I, HENRY W. UNCKLES, a citizen of the United States, and a resident of the city of New York, in the county 5 and State of New York, have invented certain new and useful Improvements in Carbureters, of which the following is a specification.

My invention relates to carbureters, and 10 more particularly to carbureters for internal combustion engines.

One of the objects of the invention is to provide a carbureter which will produce thorough vaporization of the hydrocarbon 15 and thorough mixture of the same with the air.

Another object of the invention is to provide a carbureter of great elasticity of operation; that is, one by means of which the 20 engine will work smoothly over a wide range of speeds.

I carry out these objects in the preferred embodiment of my invention as herein illustrated, by providing a tubular member of 25 relatively small cross-sectional area below the mixing chamber so as to form a lower extension of the main fuel passageway, and at the lower end of this tubular member I provide a nozzle member having nozzle 30 openings therethrough communicating respectively with the hydrocarbon and air so as to cause jets of hydrocarbon and air to be impinged one against the other at the lower end of the tubular member where the 35 velocity of the gases is highest. This causes thorough vaporization and mixture of the gas and air as they are discharged into and pass through this member. I also provide a shunt path for the air to this tubular 40 member around the nozzle member so as to regulate the amount of air passing through the nozzle member, and I also provide one or more branch passages communicating with the mixing chamber above the tubular 45 member, for supplying auxiliary air to the mixing chamber. In the preferred embodiment of the invention I control the auxiliary air through these passages by means of spring-controlled valves one of which is operated responsive to less suction than the 50 other. In order to increase the vaporization of the gases, I also provide a heating

coil around the tubular member below the mixing chamber.

My invention will be more readily understood and further objects of the invention will more fully appear from the following description taken in connection with the accompanying drawings illustrating the preferred embodiment of the invention, and in 55 which—

Figure 1 is a longitudinal sectional view of the carbureter; Fig. 2 is a longitudinal sectional view taken on line 2—2 of Fig. 1; Fig. 3 is a cross-sectional view taken on line 65 3—3 of Fig. 2; and Fig. 4 shows a diagram of electric circuits controlling the heating coil.

Referring to the drawings, Fig. 1, the shell of the carbureter comprises an upper portion 4 and a lower portion 5 secured to an intermediate portion 6. The upper portion 4 is provided with a mixing chamber 7 forming a part of the main passageway for the fuel mixture to the engine. This mixing chamber is surrounded by a heating chamber 8 adapted to be heated preferably by the exhaust gases from the engine, which is supplied through openings 9, 10 (Fig. 2), and within the passageway is mounted a 80 throttle valve 11. The intermediate part of the shell 6 is provided with an inner supporting frame in the form of a cylindrical extension 12 arranged below and in alignment with the mixing chamber, within which 85 is detachably mounted a sleeve 13 adjustably secured to the cylindrical extension 12 by means of a set screw 14, the sleeve and the cylindrical extension 12 forming between them an annular chamber 15 for the purpose 90 hereinafter referred to. Within the sleeve is threaded a tubular member 16 by means of threads 17. This tubular member has a bore 18 of relatively small cross-sectional area which flares upwardly from the point 95 19, and below the point 19 the tubular member is provided with a downwardly and outwardly flaring shoulder 20. This bore may be regarded as a lower extension of the main passageway, and is made of reduced 100 cross-sectional area to insure high velocity of the air at this point. The sleeve 13 and the tubular member 16 form between them an annular heating chamber 21 which is

provided with an electric heating coil 22 submerged in a suitable liquid such as oil, which serves to distribute the heat from the coil around the tubular member. One end 5 of the coil is connected in a suitable circuit, as hereinafter mentioned, by means of a wire 23, while the other end of the coil is preferably grounded to the carbureter. The annular chamber 15 above mentioned serves 10 to check conduction of the heat to the frame 12.

Below the tubular member I provide a nozzle member 24 which, in the preferred embodiment of the invention, contains hydrocarbon and air discharge openings. In 15 the embodiment of the invention shown, this nozzle member is provided with a cupped portion 25 at its upper end, and into this cupped portion the hydrocarbon and air are 20 discharged in the form of jets by means of nozzle or discharge openings 26-26, 27-27. In the form of the invention shown, the nozzle openings 26-26 communicate with a hydrocarbon tank 28 through restricted 25 branch passageways 29-29 and passageways 30, 31 (Fig. 2), while the air discharge openings 27-27 communicate with lower passageway 32 through restricted passageways 33-33 extending through the nozzle 30 member, the passageway 32 having an air intake opening 34. In the present embodiment of the invention the nozzle discharge openings 26-26 for the hydrocarbon are arranged in the same plane and at an angle of 35 inclination to discharge the hydrocarbon jets one against the other, while the air discharge openings 27-27 are arranged in the same plane and at an angle of 90° to the plane of the hydrocarbon nozzle openings so 40 as to discharge the air jets one against the other and against the hydrocarbon jets, the arrangement being such that the air and hydrocarbon jets are directed toward a common point slightly in elevation of a plane 45 cutting the center of the discharge openings. The nozzle-containing member 24 is made somewhat cone-shaped so that its outer tapering surface 35 will form with the surrounding tapering surface 20 of the tubular 50 member, an annular air passage 36 in shunt to the air discharge openings 27-27, through which passage the balance of the primary air which is not discharged through the nozzle openings, may flow. The purpose of this 55 is to obtain a suitable amount of primary air while permitting of the use of relatively restricted air discharge openings in the nozzle member. It is desirable to adjust the size or capacity of this shunt opening to 60 regulate the amount of air passing through the discharge openings 27-27 without limiting the total amount of primary air supplied, and this I do by providing means for relative adjustment between the tubular

member 16 and the nozzle-containing member. I accomplish this by making the sleeve 13 carrying the tubular member 16 adjustable within its cylindrical support 12, as above described.

The nozzle-containing member 24 is 70 threaded in the upper end of a tubular connection piece 38 provided with a flange 39 which rests upon a supporting cross piece 40 bored out to receive the connection piece 38, and the connection piece is held firmly in 75 place in this support by means of a nut 41. On the lower end of the connection piece 38 there is threaded a needle valve supporting member 42 having a packing-box or chamber 43 at its upper end containing packing 80 around the needle 44 which is threaded at 45 within the needle-supporting member 42. This needle support is threaded in the lower wall of the carbureter at 46 and is held locked in place by means of a nut 47. The 85 needle 44 extends through its supporting member through the packing-box and the member 38 into the passageway 30, and is provided at its upper end with the usual tapering portion 48 for controlling the flow of 90 the hydrocarbon from passageway 30 to the restricted passageways or openings 29 through the nozzle member.

In the present embodiment of my invention I provide auxiliary air valves located in 95 branch passageways 50, 50' which communicate with the mixing chamber just above the tubular member 16, into which the air and gas nozzles discharge. These branch passages 50, 50' have their lower side walls 100 formed in the intermediate portion of the carbureter 6, while the upper wall of the passageway is formed by the lower surface 51 of the upper section of the carbureter. The lower walls of the branch passages are 105 provided with auxiliary air ports having valve seats 53, 53' against which disk valves 54, 54' are adapted to be seated by means of springs 55, 55'. These auxiliary air valve disks are mounted respectively on stems 56, 110 56' of usual construction. The springs 55, 55' press at their upper ends against sleeves 57, 57' which are threaded within tubular extensions 58, 58' and are provided with heads 59, 59' whereby the pressure of the 115 springs may be adjusted. One of the valves 54' is provided with a much lighter spring than the other valve, for the purpose of having this auxiliary air valve operate responsive to less suction than the other, and the stem 56' of this valve is provided with means, such as a nut 60 threaded onto the stem, for limiting the upward movement of the valve. By this arrangement the valve 54' will be opened at comparatively low 120 speeds and held open at higher speeds, while the other auxiliary air valve 54 will only be opened at the higher speeds. The

auxiliary valve ports communicate with branch passageways 61, 61' leading from the lower passageway 32, and the air intake opening 34 to this latter passageway is controlled by means of a butterfly valve 62 normally held open by means of a spring 63, but provided with lever mechanism 64 by means of which the passageway may be closed, or partially closed, in starting up the engine.

Since I have provided a heating jacket around the mixing chamber for heating the mixture by means of exhaust gases after the engine is running, it is not necessary to continue the electric heating coil in circuit after the engine has warmed up; and I have provided means for automatically disconnecting the heating coil at this time. The means for doing this is illustrated in Figs. 2 and 4, where it will be seen that I have provided a mercury thermometer 65 sealed within a tube 66 which is threaded in the wall of the heating chamber. This thermometer is provided with contacts 67, 67' located at a suitable distance along the bore of the thermometer and connected with wires 68, 69 for controlling the circuit of the heating coil as follows: The wire 23 leads from one end of the heating coil 22 to one pole of battery 70, the other pole of which is connected through wire 71 to switch contact 72, while the grounded end of the coil 22 is connected through wire 73 to switch contact 74. These contacts are adapted to be closed by a switch 75 which is connected to the core 76 of solenoid 77, and this solenoid is arranged with contacts 67, 67' in a branch circuit around the coil 22 by means of wires 69, 68 and 78. When it is desired to close the circuit to the heating coil 22, the switch 75 is manually closed and the heating coil remains in circuit until the temperature of the heating chamber 8 with which the thermometer is connected, rises to a sufficient point to cause expansion of the mercury to close contacts 67, 67', whereupon the branch circuit through the solenoid 77 is closed and the solenoid, by drawing down on its core, opens the switch 75 to break the circuit to the heating coil 22, as well as that through the solenoid.

While I have described my invention with particularity in connection with the preferred embodiment of the same as herein shown, it will be obvious to those skilled in the art after understanding my invention, that various changes and modifications may be made, and I do not wish to be understood as limiting myself to the embodiment of the invention herein illustrated; and I aim in the appended claims to cover all changes and modifications within the scope of my invention.

Having thus described my invention, what I claim as new and desire to secure by Letters Patent, is—

1. In a carbureter, the combination of a passageway for fuel mixture, a plurality of restricted passageways communicating with said first passageway and having openings adapted to discharge jets of air into said first passageway one against the other, a hydrocarbon supply pipe, and a plurality of nozzles communicating with said pipe and in close proximity to the air discharge openings adapted to discharge jets of hydrocarbon against the air jets, whereby the jets of hydrocarbon and air are caused to impinge upon and intermingle with each other.

2. In a carbureter, the combination of a passageway for fuel mixture having a lower extension of reduced cross-sectional area, a restricted passageway having a discharge opening within said extension for discharging a jet of air into the same, a shunt passageway also communicating with said extension above the discharge opening of the restricted passageway for conveying air to the extension, a source of hydrocarbon supply, and a nozzle communicating with the same and located in close proximity to the restricted air opening and adapted to discharge a jet of hydrocarbon against the air jet.

3. In a carbureter, the combination of a passageway for fuel mixture, a restricted passageway communicating with the same for discharging a jet of air therein, a shunt passageway also communicating with said first passageway above the opening of the restricted passageway for conveying air around the same to the first passageway, a source of hydrocarbon supply, a nozzle communicating with the same and located in close proximity to the restricted air opening and adapted to discharge a jet of hydrocarbon against the air jet, and means for adjusting the size of the shunt passageway to regulate the amount of air to be shunted around the air jet opening.

4. In a carbureter, the combination of a main passageway for fuel mixture having a lower extension of reduced cross-sectional area, a plurality of restricted passageways having discharge openings into said extension and arranged in close proximity one to the other for discharging jets of air one against the other into the extension, a passageway below said restricted air openings and communicating therewith and having an air intake opening, a port communicating with the main passageway above the said air discharge openings and provided with a spring-controlled valve for admitting auxiliary air, a source of hydrocarbon supply and one or more nozzles communicating therewith and arranged in close prox-

imity to the discharge openings of the restricted passageways so as to discharge one or more jets of hydrocarbon against the air jets.

5. In a carbureter, the combination of a main passageway for fuel mixture having a lower extension of reduced cross-sectional area, a restricted passageway having a discharge opening communicating with the extension for discharging a jet of air therein, a source of hydrocarbon supply, a nozzle communicating therewith and arranged in close proximity to the discharge opening for discharging a jet of hydrocarbon against the air jet, and a shunt passageway around the restricted air passageway and having a discharge opening above that of the restricted passageway for supplying air to the extension, an air passageway below said restricted and shunt passageways communicating therewith and provided with an air intake opening, and an auxiliary air port communicating with the main passageway above the nozzle.

25 6. In a carbureter, the combination of a main passageway having a lower extension of reduced cross-sectional area, said extension being provided with a plurality of restricted passageways having air discharge openings arranged in close proximity one to the other for discharging jets of air into the extension, a passageway communicating with the lower ends of said restricted passageways and having an air intake opening, and 30 an auxiliary air port communicating with the main passageway above said air discharge openings, a spring-controlled valve controlling said port, a source of hydrocarbon supply, a nozzle communicating therewith and arranged in close proximity to said air discharge openings to discharge a jet of hydrocarbon against the air jets, and a shunt passageway communicating with the air intake opening and having a discharge 35 opening above the hydrocarbon nozzle and air jet openings for conveying air around the same.

7. In a carbureter, the combination of a passageway for fuel mixture, and a member 50 located within the passageway and having a plurality of nozzle openings therein for discharging jets of hydrocarbon one against the other within the passageway, and also having a plurality of other nozzle openings therethrough for discharging air jets against the hydrocarbon jets.

8. In a carbureter, the combination of a passageway for fuel mixture, and a detachable member located within the passageway 55 and having two nozzle openings therein lying substantially in the same plane for discharging jets of hydrocarbon one against the other, said member also having two air nozzle openings therethrough for discharging

air jets against the hydrocarbon jets, said 65 air nozzles lying in substantially the same plane at approximately 90° to the plane of the hydrocarbon nozzles.

9. In a carbureter, the combination of a passageway for fuel mixture, a member located within the passageway and having a plurality of nozzle openings therein for discharging jets of hydrocarbon one against the other within the passageway, and also having a plurality of other nozzle openings therethrough for discharging air jets against the hydrocarbon jets, said nozzle-containing member being operatively related to the walls of the passageway so as to provide a shunt passage for air around said member, and means whereby relative adjustment may be had between said member and an adjacent portion of the passageway to adjust the size of the shunt passage.

10. In a carbureter, the combination of a passageway for fuel mixture having an air intake opening at its lower end, a detachable member located within the passageway and having a nozzle opening therein for discharging a jet of hydrocarbon within the passageway, and also having another nozzle opening therethrough communicating with the passageway below said member for discharging an air jet against the hydrocarbon jet, said nozzle-containing member being operatively related to the walls of the passageway so as to provide a shunt passage for air around said member, and means whereby relative adjustment may be had between said member and an adjacent portion of the passageway to adjust the size of the shunt passage.

11. In a carbureter, the combination of a passageway for fuel mixture, a member located within the passageway and having a plurality of nozzle openings therein for discharging jets of hydrocarbon one against the other within the passageway, and also having a plurality of other nozzle openings therethrough for discharging air jets against the hydrocarbon jets, said passageway having a portion of reduced cross-sectional area provided with a shoulder adjacent the nozzle-containing member forming with said member a shunt passage for air around said member, and means whereby relative adjustment may be had between the nozzle member and said shoulder to adjust the size of the shunt passage.

12. In a carbureter, the combination of a passageway for fuel mixture, a tubular member within the passageway having a downwardly and outwardly flaring annular shoulder, a nozzle member located within the passageway below the shoulder and having an upwardly tapering outer surface forming with the tapering shoulder of the first member a shunt air passage, said nozzle mem-

ber having a plurality of nozzle openings therein for discharging jets of hydrocarbon one against the other within the first passageway, and also having a plurality of other nozzle openings therethrough for discharging air jets against the hydrocarbon jets, and means for relative adjustment between the tubular member and nozzle member to vary the size of the discharge opening 10 of the shunt passage between the two.

13. In a carbureter, the combination of a mixing chamber forming a portion of the main passageway for fuel mixture, a tubular member located within the passageway below the mixing chamber and having a bore of less cross-sectional area than the mixing chamber, forming an extension of the passageway below the chamber, and a nozzle member located at the lower end of the bore 20 and having air and gas nozzle openings therethrough for discharging air and gas jets one against the other at the lower end of the bore, the lower end of said tubular member surrounding the nozzle member and 25 forming therewith an air passage around the nozzle openings for discharging air into the lower end of the bore.

14. In a carbureter, the combination of a mixing chamber forming a part of the main 30 passageway for fuel mixture, an extension of the passageway below the same of reduced cross-sectional area, a nozzle for discharging hydrocarbon within said extension, a passageway below the same having 35 an air intake opening, a plurality of branch passageways communicating with the mixing chamber and having auxiliary air ports, and spring-controlled valves governing the same, one of said valves being operated by 40 less suction than the other so as to respond at lower speeds while the other valve is operated only at higher speeds.

15. In a carbureter, the combination of a mixing chamber forming a part of the main 45 passageway for fuel mixture, a tubular member secured within the passageway below the mixing chamber and having a bore of relatively small cross-sectional area, a nozzle member located at the lower end of the bore 50 and having air and gas nozzle openings therethrough for discharging hydrocarbon and air jets into the bore, a plurality of branch passageways communicating with the mixing chamber and having auxiliary 55 air ports, and spring-controlled valves governing the same, one of said valves being operated by less suction than the other so as to respond at lower speeds while the other valve is operated only at higher speeds.

16. In a carbureter, the combination of a mixing chamber forming a part of the main 60 passageway for fuel mixture, an inner frame below said extension, a detachable tubular member secured to said frame and having a

bore of relatively small cross-sectional area 65 in alignment with the mixing chamber, a nozzle member located at the lower end of the tubular member and surrounded by the lower end of the same and having a plurality of hydrocarbon and air nozzle openings 70 therethrough for discharging jets of hydrocarbon and air one against the other at the lower end of said bore, branch passageways communicating with the mixing chamber and each having an auxiliary air port, a 75 spring-controlled valve for each port one of which is operated responsive to less suction than the other, and a lower passageway communicating with the auxiliary air ports and the bore of the tubular member and having an air intake opening.

17. In a carbureter, the combination of a mixing chamber forming a portion of the main passageway for fuel mixture, a detachable tubular member below the same 85 having a bore of relatively small cross-sectional area, means for delivering air to said bore, a nozzle for discharging hydrocarbon within the bore, a sleeve detachably secured to said tubular member and detachably supported within the carbureter and forming with the wall of the tubular member a chamber surrounding the bore and adapted to receive liquid, and an electric coil within said chamber for heating the liquid, whereby the 90 wall of the bore may be more efficiently heated.

18. In a carbureter, the combination with a mixing chamber, of a sleeve detachably secured within the carbureter below the mixing chamber, a tubular member detachably fitting within the sleeve and having a portion flaring upwardly and inwardly from the sleeve and then outwardly so as to form with the sleeve an annular heating chamber 100 adapted to be filled with liquid, an electric heating coil within said chamber for heating the liquid, said tubular member forming a lower extension of the main passageway below the mixing chamber, means for discharging hydrocarbon within the tubular member, and means for conveying air to the 110 tubular member.

19. In a carbureter, the combination of a passageway for fuel mixture, a heating 115 chamber in the upper part of the carbureter surrounding an adjacent portion of said passageway and adapted to receive heated fluid for heating the same, said passageway having an air intake opening, a nozzle for discharging hydrocarbon into the passageway and an electric heating coil within the carbureter and operatively related to the passageway below the said fluid-heated chamber for heating the fuel fluid before it 120 reaches said fluid-heated chamber, a circuit for said heating coil, a contact controlling said circuit, and means operatively related to 125

said contact and to the fluid-heated chamber and operated responsive to a predetermined temperature in said chamber for controlling the contact to open the circuit to the heating coil, whereby the heating coil may be automatically cut out of circuit after the engine has warmed up.

In testimony whereof, I have signed my name to this specification, in the presence of two subscribing witnesses.

HENRY W. UNCKLES.
